CLAIM

The ornamental design for a modular telephone set, as shown and described.

DESCRIPTION

FIG. 1 is a perspective view of modular telephone set showing my new design wherein the block has been partially inserted into the base;

FIG. 2 is a perspective view thereof wherein the block is completely inserted into the base;

FIG. 3 is an isometric view of the base of the design, showing the front;

FIG. 4 is a top view of the base;

FIG. 5 is a bottom view of the base;

FIG. 6 is a right side view of the base, the left side being a mirror image thereof;

FIG. 7 is an isometric view of the block;

FIG. 8 is a right side of the block, the left side being a mirror image thereof;

FIG. 9 is a right side elevational view of that shown in FIG. 2, the left side being a mirror image thereof;

FIG. 10 is a top plan view of the block; and,

FIG. 11 is a bottom plan view of the block.

The rear of the block and the rear of the base are not considered to be a part of my claimed design.

The base and block have been shown separate in FIGS. 3-8 and 10-11 for convenience of illustration.
